UNITED STATES PATENT OFFICE.

WILLIAM R. CHANCELLOR, OF CHICAGO, ILLINOIS, ASSIGNOR OF ONE-HALF TO
RICHARD H. BAYLOR, OF MILWAUKEE, WISCONSIN.

FLOOR-WAXING MACHINE.

Application filed May 18, 1925. Serial No. 31,226.

To all whom it may concern:

Be it known that I, WILLIAM R. CHANCELLOR, a citizen of the United States of America, and a resident of Chicago, county of Cook, and State of Illinois, have invented a new and useful Improvement in Floor-Waxing Machines, of which the following is a specification.

This invention relates to portable power operated machines for waxing and polishing floors. The purpose of the invention is to provide a light, complete machine, which may be easily manipulated, and well adapted to take the place of manually operated devices for waxing and polishing floors, and thereby saving immense labor in such work. It is also a purpose of the invention to provide a simple and efficient means for feeding wax from a wax container on the machine, in the required quantity to a brush which serves to apply the wax to the floor before it is spread and polished by a separate brush carried by the machine; and to provide a convenient means for causing the wax applying brush to become operative and inoperative, as required, and to raise and lower the brush out of and into contact with the floor.

The objects of the invention are fully attained by the constructions such as shown in the drawing, wherein:

Fig. 1 is a plan view of the machine with its casing removed.

Fig. 2 is a side view of the construction shown in Fig. 1.

Fig. 3 is a longitudinal sectional detail showing the wax supply container and wax applying brush cooperating therewith.

Fig. 4 is a side view of a spraying and polishing brush having a cloth covering applied thereto which is used for the final polishing operation.

The principal features of the construction as may be seen from the drawing, are a suitable supporting base mounted upon casters of suitable height for making room for the rotating brushes mounted below the supporting base. One of these casters is free to swing around a vertical axis so that the machine may be easily guided into the desired direction. A motor is mounted upon the supporting base, and is belted to a vertical spindle adapted to removably receive spreading and polishing brushes. Intermediate the

motor and said vertical spindle is a wax supply container, and below this container on a horizontal axis is a wax applying brush. This brush is carried by an arm pivoted to the supporting frame, so that it may be swung downwardly against spring action from its normal position, into contact with the floor. Such motion is transmitted to the waxing brush at desired intervals by the operator drawing upwardly on a lever hinged to the operating handle of the machine, by which the machine is guided over the floor, this lever being connected by a wire with the waxing brush supporting arm. The downward motion of the waxing brush causes a pulley belted thereto to come into engagement with the driving belt for the purpose of rotating the waxing brush. The wax container is slidably mounted above the waxing brush in order to follow the same in its downward and upward motions, and is preferably provided at its lower side, where it cooperates with the waxing brush with longitudinal slots or some similar arrangement for allowing only a limited contact between the brush and the wax.

The bottom of the wax container is partly curved around the waxing brush and provision is made for adjusting the container horizontally toward the brush so that its lower edge may serve to wipe off the excess wax from the brush.

As illustrated in the drawing, the above mentioned arrangement includes a supporting base 1, provided with casters 2 and 3, the latter being swiveled for rotation around a vertical axis. The guiding handle 4 extends upwardly from one end of base 1, and is provided with a grip 5, to which is pivoted a small arm or lever 6, which may be drawn upwardly toward the grip 5 by the fingers of the operator. The arm 6 is connected by a wire 7 passing through a flexible conduit 8, with a lever 9 pivoted to the platform 1 at 10. Rotatably mounted in the lower end of lever 9 is a waxing brush 11 carrying a pulley 12, and at the upper end of arm 9 is a pulley 13, connected with pulley 12 by a belt 14. Rigid with pulley 13 is another preferably larger pulley 15, in position for engagement with a drive belt 16, when the arm 9 is rocked to carry the waxing brush downwardly. The arm 9 and parts carried there-

by are normally held in the position in which they are shown in Fig. 2 by the spring 17. The driving belt 16 passes around a motor pulley 18, idler wheels 19, and a pulley 20, fast to the vertical spindle 21. This spindle has its bearing in platform 1, and at its lower end is arranged for receiving different polishing appliances, such as the brush 22. When the motor 23 is in operation, the brush 22 is therefore rapidly rotated around a vertical axis, but brush 11 normally remains idle, because the pulley 15 is normally out of contact with belt 16. When the lever 6, attached to the grip 5, is drawn upwardly, pulley 15 becomes effective with respect to belt 16, and motion from the pulley 15 is transmitted to the brush 11, through the belt 14 and pulley 12.

A suitable opening 24 is provided in base 20 1 at the location of the waxing brush 11, and a wax receptacle 25 is mounted above the brush at this opening. This receptacle is in box form, and provided with an apertured flange 26, through which passes vertical posts 27, extending upwardly from the base 1. The receptacle 25 is free to slide upon these posts and therefore moves up and down with the wax applying brush 11. The wax container 25 is more or less closed 30 at the bottom, and the point of contact with the brush 11, preferably by a plurality of longitudinally extending and upwardly curved wires 28, or other suitable means for leaving openings or longitudinally extending slots 29 at the bottom of the container. The bristles of the brush 11 may extend slightly into the slots to pick up a limited quantity of wax during rotation of the brush. The feed of the wax toward the 40 brush is slowly provided for by a movable weight 29, resting on the upper surface of the wax 30. When the wax brush supporting arm 9 is swung by means of the connection with arm 6 at handle 5, downward motion of drive belt 16 is limited by an idler 31.

The posts 27 upon which the wax container 25 is slidably supported, are connected together at their lower ends by a part 32 extending at right angles to the posts into 50 a slot 33 in platform 1. This arrangement provides for adjustment of the wax container so its lower edge 34 may be brought more or less into contact with the ends of the bristles of brush 11 and serve to limit the 55 amount of wax carried downwardly by the brush. The set screw 35 is for permanently fixing the structure after the adjustment is made.

In Fig. 4, a brush such as the spreading or polishing brush 22, is shown provided 60 with a cloth cover 32, which arrangement is employed for the final polishing operation. This cover is merely in the form of a bag, having an elastic band hemmed into it at 65 its open end 33.

The motor receives current through a flexible conduit under the control of a switch 34, as is common in vacuum cleaners and other portable devices for operating upon a floor.

In the operation, the closing of the motor circuit results in the rapid rotation of brush 22, but brush 11 is only driven at such times as it is lowered by drawing the lever 6 toward grip 5. In waxing a floor it is necessary to only occasionally lower brush 11, for instance, in order to apply a small quantity of the wax; then brush 22 is utilized for evenly spreading the wax. After the spreading operation is completed, other 80 brushes are applied to spindle 21 for polishing. When brush 10 is lowered by drawing on wire 7, pulley 15 is drawn into engagement with belt 16, resulting in transmitting rotary motion to the brush 11 through the 85 belt 14. Rotation of the brush causes it to carry wax from the container 25 to the floor, this container being free to follow the brush in its downward motion.

Although but one specific embodiment of 90 this invention has been herein shown and described, it will be understood that numerous details of the construction shown may be altered or omitted without departing from the spirit of this invention as defined by 95 the following claims.

I claim:

1. A floor waxing machine comprising a suitable operating handle and base, said base being provided with supporting casters 100 and supporting a motor, a vertical spindle mounted for rotation in said base and carrying a brush below the base for contact with the floor and also carrying a pulley, a belt connecting said pulley with a motor, an arm pivoted to said base and carrying at its lower end a waxing brush mounted for rotation on a horizontal axis, said arm also carrying a pulley in position to engage said belt when the arm is rocked around its pivot, and means 110 for rocking said arm around its pivot, whereby the brush carried thereby is lowered into operative position and the pulley is engaged with said belt.

2. A floor waxing machine comprising a suitable operating handle and base, said base being provided with supporting casters and supporting a motor, a vertical spindle mounted for rotation in said base and carrying a brush below the base for contact with the floor and also carrying a pulley, a belt connecting said pulley with the motor, an arm pivoted to said base and carrying at its lower end a waxing brush mounted for rotation on a horizontal axis, said arm also carrying a pulley in position to engage said belt when the arm is rocked around its pivot, means for rocking said arm around its pivot, whereby the brush carried thereby is lowered into operative position, and the pul- 115 120 125 130

ley is engaged with said belt, and means for transmitting motion from said pulley to said waxing brush.

3. A floor waxing machine comprising a suitable operating handle and base, said base being provided with supporting casters and supporting a motor, a vertical spindle mounted for rotation in said base and carrying a brush below the base for contact with the floor and also carrying a pulley, a belt connecting said pulley with the motor, an arm pivoted to said base and carrying at its lower end a waxing brush mounted for rotation on a horizontal axis, said arm also carrying a pulley in position to engage said belt when the arm is rocked around its pivot, means for rocking said arm around its pivot, whereby the brush carried thereby is lowered into operative position and the pulley is engaged with said belt, and a wax container mounted above said waxing brush and adapted to move downwardly with the waxing brush.

4. A floor waxing machine comprising a suitable operating handle and base, said base being provided with supporting casters and supporting a motor, a vertical spindle mounted for rotation in said base and carrying a brush below the base for contact with the floor and also carrying a pulley, a belt connecting said pulley with the motor, an arm pivoted to said base and carrying at its lower end a waxing brush mounted for rotation on a horizontal axis, said arm also carrying a pulley in position to engage said belt when the arm is rocked around its pivot, means for rocking said arm around its pivot, whereby the brush carried thereby is lowered into operative position, and the pulley is engaged with said belt, and a wax container mounted above said waxing brush and adapted to move downwardly with the waxing brush, said wax container being slidable along a vertical post extending upwardly from the base.

5. A floor waxing machine comprising a suitable operating handle and base, said base being provided with supporting casters and

supporting a motor, a vertical spindle mounted for rotation in said base and carrying a brush below the base for contact with the floor and also carrying a pulley, a belt connecting said pulley with the motor, an arm pivoted to said base and carrying at its lower end a waxing brush mounted for rotation on a horizontal axis, said arm also carrying a pulley in position to engage said belt when the arm is rocked around its pivot, means for rocking said arm around its pivot, whereby the brush carried thereby is lowered into operative position, and the pulley is engaged with said belt, and a wax container mounted above said waxing brush and adapted to move downwardly with the waxing brush, said wax container being slidable along a vertical post extending upwardly from the base, the bottom of said wax container being provided with openings extending in the direction of rotation of the waxing brush.

6. A floor waxing machine comprising a suitable base supporting a motor and suitable waxing and polishing brushes, a drive connection between said motor and brushes, a wax container for cooperating with the waxing brush, a support for said container permitting vertical movement of said container, and means for adjusting said container support in a horizontal direction toward and away from said waxing brush.

7. A floor waxing machine comprising a suitable base supporting a motor and suitable waxing and polishing brushes, a drive connection between said motor and brushes, a wax container for cooperation with the waxing brush, a support for said container, and means for adjusting said container support in a horizontal direction toward and away from said waxing brush, the bottom of said wax container being curved part way around said waxing brush and being provided with openings extending in the direction of rotation of the brush.

Signed at Chicago this 11th day of May, 1925.

WILLIAM R. CHANCELLOR.
